UNITED STATES PATENT OFFICE.

ELWOOD B. AYRES AND THOMAS H. RHOADS, OF PHILADELPHIA, PENNSYLVANIA, AS
SIGNORS TO PROCTOR & SCHWARTZ, INC., OF PHILADELPHIA, PENNSYLVANIA, A
CORPORATION OF PENNSYLVANIA.

MACHINE FOR DRYING AND CONDITIONING MATERIAL.

Application filed April 26, 1923. Serial No. 634,765.

To all whom it may concern:

Be it known that we, ELWOOD B. AYRES and THOMAS H. RHOADS, citizens of the United States, residing in Philadelphia, Pennsylvania, have invented certain Improvements in a Machine for Drying and Conditioning Material, of which the following is a specification.

Our invention relates to certain improvements in machines for drying and conditioning material, such as artificial silk, which is wound on glass cylinders.

One object of our invention is to provide mechanism for carrying the cylinders through a drying apparatus so that the artificial silk will be dried and conditioned properly.

A further object of our invention is to provide suspended carriers for supporting the glass cylinders.

In the accompanying drawings:

Fig. 1 is a plan view of our improved machine for drying and conditioning materials;

Fig. 2 is a side view;

Fig. 3 is a transverse sectional view on the line 3—3, Fig. 2;

Fig. 4 is a sectional view on the line 4—4, Fig. 2;

Fig. 5 is a side view of one of the carriers; and,

Fig. 6 is an end view of a carrier.

Our improved machine consists of a casting 1 divided into two sections by a longitudinal partition 2 extending the full length of the machine. Located some distance on each side of the central partition 2 are partitions 3 having openings 4 in which are located circulating fans 5 mounted on horizontal shafts 6. The shafts 6 are geared to a longitudinal shaft 7 by means of spiral gears 8, shown in Fig. 4. At each end of the machine are motors 9, which drive the shaft 7.

10 designates longitudinal overhead rails from which the carriers 11 are suspended. Each carrier consists of a frame 12 having arms 13 recessed to receive the glass cylinders 14 upon which the material to be dried and conditioned is wound. In the present instance, there are seven arms 13 in each series. The arms of each series are connected by bars 15, as clearly shown in Figs. 5 and 6.

16 designates trolleys pivotally connected to the frame 12 of each carrier. The wheels 17 of the trolleys travel on the rails 10. At the lower end of each carrier are wheels 18, which are mounted on vertical axles. At each side of the frame 12 are rails 19 spaced some distance from the wheels so that the carriers can swing to a limited extent. There are three longitudinal rails in each section of the machine, although the number of rails may be increased or diminished according to the size of the machine.

20 designates the upper, horizontal partitions and 21 designates the lower, horizontal partitions forming upper circulating chambers 22 and lower circulating chambers 23. These chambers connect with the fan chamber 24 at the center of the machine and with a circulating space 25 at each side of the machine. The two partitions 20 and 21 form a drying chamber 26, in which the carriers travel. The air circulates in the several chambers, as shown clearly by the arrows, Fig. 3.

In the upper, circulating chamber 22 are steam coils 27 and in the lower, circulating chamber 23 are steam coils 28. These coils heat the air in circulation.

The machine is divided into compartments. There is a long drying compartment *a*, indicated in Fig. 1; a short cooling compartment *b*; a regaining compartment *c*, in which a certain amount of moisture is added, and a conditioning compartment *d*. Communicating with the drying compartment are exhaust flues 29, in which are fans 30 that remove the moist air from the drying compartment. Communicating with the cooling compartment are flues 31 that admit fresh air to said compartment. At the center of the machine are flues 32 that allow the air to exhaust from the cooling compartment, Fig. 4.

33 designates temperature controllers, which are located in the drying compartment *a*. 34 designates recording wet and dry bulb controllers, which are located in the regaining compartment. 35 designates recording wet and dry bulb controllers located in the conditioning compartment.

The operation is as follows: The fans circulate the air in the direction indicated by the arrows. The carriers are loaded with the glass cylinders on which the artificial

silk, or other material, to be dried, is wound. These carriers are fed intermittently through the machine. At the feed end of the machine is an automatic pushing device 36, of any suitable type, which pushes the carriers forward a certain distance to allow another carrier to be placed in the machine. Doors 37 are provided at the feed end of the machine and doors 38 are provided at the discharge end of the machine.

By this mechanism, the artificial silk, or like material, is dried properly and is conditioned as it passes through the machine.

We claim:

1. The combination in a machine for drying and conditioning material, of a casing; a longitudinal partition dividing the casing into two sections; a longitudinal partition in each section having fan openings; fans in said openings; means for driving the fans; horizontal partitions extending part way across the upper portion of each section and another horizontal partition extending part way across the sections near the lower ends thereof so as to cause the air to circulate; a series of rails extending longitudinally in each section; carriers suspended from the rails, said carriers having arms; and cylinders, mounted on the arms, carrying the material to be dried and conditioned.

2. The combination of a casing; a longitudinal partition dividing the casing into two sections; means for circulating air in each section; coils for heating the air in circulation; overhead rails in each section; carriers suspended from the rails, said carriers having arms; and cylinders, mounted on the arms, carrying the material to be dried and conditioned.

3. The combination of a casing; a longitudinal partition within the casing stopping short of the top and bottom thereof and having fan openings therein; horizontal partitions extending from the longitudinal partition at points above and below the fan openings and stopping short of the opposite side of the drier section; heating pipes for heating air in circulation; overhead rails; carriers suspended from said rails in the space between the two horizontal partitions; and means, on the carrier, for supporting material to be dried.

4. The combination of a casing; means for circulating air in the casing; means for

heating the air in circulation; an overhead rail; and a series of carriers suspended from the rail, said carriers having means for supporting material to be dried, said casing being divided longitudinally into four compartments, the first being a drying compartment, which has means for exhausting air therefrom, the second a cooling compartment, which has inlets for fresh air at one side and outlets for air at the opposite side, the third a regaining compartment, and the fourth a conditioning compartment.

5. The combination of a casing; a longitudinal partition dividing the casing into two sections; a longitudinal partition in each section stopping short of the top and bottom thereof and having fan openings therein; two horizontal partitions extending from the partitions having the fan openings therein to a point short of the opposite side of each section; a series of overhead rails above the upper partitions; guides at the lower partitions; and a series of carriers mounted on the rails and extending between the lower guides, said carriers having means for supporting material to be dried.

6. The combination in a machine for drying and conditioning material, of a casing; means for circulating air in the casing; means for heating the air in circulation; an overhead rail extending longitudinally within the casing; a series of carriers suspended from the rail, each carrier consisting of a frame having swiveled trolleys; trolley wheels mounted on the rails and having guide wheels at the lower end; arms on the frame for supporting the material to be dried and conditioned; and longitudinal guides in the lower portion of the casing for guiding the frame of the carrier.

7. The combination in a machine for drying and conditioning material, of a casing; means for circulating air in the casing; means for heating the air in circulation; an overhead rail extending longitudinally through the casing; a series of carriers suspended from the rail, each carrier consisting of a frame; and a series of arms extending on each side of the frame, each of said arms being recessed to receive cylinders on which the material to be dried and conditioned is wound.

ELWOOD B. AYRES.
THOMAS H. RHOADS.
